UNITED STATES PATENT OFFICE.

HENRY M. DIXON, OF NEW YORK, N. Y.

TOY CAP-EXPLoder.

SPECIFICATION forming part of Letters Patent No. 332,063, dated December 8, 1885.

Application filed April 29, 1885. Serial No. 163,865. (No model.)

To all whom it may concern:

Be it known that I, HENRY M. DIXON, of the city, county, and State of New York, have invented a new and useful Improvement in 5 Toy Paper-Cap Exploders, of which the following is a full, clear, and exact description.

Reference is to be had to the accompanying drawings, forming a part of this specification, in which similar letters of reference indicate 10 corresponding parts in all the figures.

Figure 1 is a side elevation of one of my toy paper-cap exploders, and showing in dotted lines the position of the bird after the paper cap has been exploded. Fig. 2 is a sectional 15 side elevation of the same. Fig. 3 is a sectional end elevation of the same, taken through the line $\alpha\alpha$, Fig. 1. Fig. 4 is a plan view of a part of the holder.

The object of this invention is to provide 20 toy paper-cap exploders made in such a manner that when the paper cap is exploded the representation of a bird perched upon the toy will fall off as if shot, and the sparks will be prevented from flying about.

25 The invention consists in the construction and combination of the various parts of the toy, as will be hereinafter fully described and then claimed.

A is the stock or holder, which is made 30 semi-tubular, and with an open rear end and a closed forward end, which serves as an anvil for the paper cap to be exploded against. Upon the lower side of the rear end of the holder A is formed a handle, B, for holding 35 the toy while being used.

C is a rod, which is made somewhat longer than the holder A, and of such a size as to slide readily in the groove of the said holder. To the lower side of the forward part of the 40 rod C is attached a guide-pin, D, which passes through and slides in a guide-slot, E, in the bottom of the holder A, and is made with a head to prevent it from being withdrawn from the said slot E, and thus keep the rod C in 45 place in the said holder.

In the holder A, at one side of the rear end of the slot E, is formed a recess, F, to receive the pin D when the rod C is drawn back and hold the said rod in that position while a 50 paper cap is being placed against the inner side of the closed forward end of the holder A.

Upon the middle part of the rod C is placed a spiral spring, G, the forward end of

which is secured in the rear end of the slot E, or to some other part of the rear end of 55 the holder A. The rear end of the spring G is secured to the rod C at a suitable distance from its rear end.

To a loop, H, formed upon the closed forward end of the holder A, is hinged an eye-strap, I, formed upon the end of the base J, upon which is formed the representation K of a bird, which stands with its head toward the rear end of the toy. The base J is made semi-tubular in form, and of such a size as to 65 fit loosely upon the upper edges of the holder A and allow the forward end of the rod C to move freely in and out beneath it, while at the same time the sparks from the paper cap will be prevented from flying about. 70

In using the toy, the rod C is drawn back and slightly turned to bring the pin D into the recess F, the bird K being in the position shown in dotted lines in Fig. 1. The paper cap is then laid against the closed forward 75 end of the holder A, and the rod C is released and allowed to move forward gently against the said paper cap to hold it in place.

When the cap is to be exploded, the bird K is swung up into the position shown in 80 Figs. 2 and 3 and in full lines in Fig. 1, and the rod C is drawn back and released quickly, when it will be thrown forward by the spring G with sufficient force to explode the paper cap, the jar throwing the bird K forward into the position shown in dotted lines 85 in Fig. 1, giving it the appearance of being shot and falling from its perch.

Having thus fully described my invention, I claim as new and desire to secure by Letters 90 Patent—

A toy paper-cap exploder constructed substantially as herein shown and described, and consisting of the semi-tubular holder A, having closed forward end, a handle, B, a slot, 95 E, and recess F, the rod C, having guide-pin D, working in the slot E, and provided with a spring, G, attached to it and to the said holder, and the bird K, having semi-tubular base J, hinged to the forward end of the said 100 holder, as set forth.

HENRY M. DIXON.
